(57) **CLAIM**

The ornamental design for a finger probe device, as shown and described.

DESCRIPTION

FIG. 1 is a front elevation view of a finger probe device showing our new design;

FIG. 2 is a rear elevation view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a top front right perspective view thereof; and,

FIG. 8 is a top rear right perspective view thereof.

The broken lines shown in the figures illustrate environmental subject matter and form no part of the claimed design.
